UNITED STATES PATENT OFFICE.

FLOYD JAMES McFARLAND, OF WEST POINT, NEW YORK.

COIN-CONTROLLED VENDING DEVICE.

Application filed October 24, 1925. Serial No. 64,636.

My present invention pertains to coin controlled vending devices, and contemplates the provision of a device of the kind described, characterized by simplicity of construction, reliability in operation, and the highly desirable feature of it being essential to deposit a predetermined number of coins aggregating a certain amount as a condition precedent to the manipulation of the device to bring about the delivery of an article of commodity such, for instance, as a package of cigarettes.

The device is particularly adapted for use in places where there are large numbers of people requiring to be served in a short space of time, it being feasible for a prospective purchaser to deposit the requisite coins and secure a package of cigarettes or the like without awaiting his turn to be served by a salesman.

Other objects and practical advantages of the invention will be fully appreciated from the following description and claim when the same are read in connection with the drawings, accompanying and forming part of this specification, in which:—

Figure 1 is a front elevation of the device constituting the best practical embodiment of my invention of which I am cognizant, and emphasizing the desirable narrowness of the improvement, so that a plurality of the devices may be arranged side by side in a space of small compass, for the vending at one point of a number of articles of commodity.

Figure 2 is a top plan view of the device.

Figure 3 is a longitudinal vertical section of the complete device, with the upright container shown as broken.

Figure 4 is a horizontal section taken in the plane indicated by the line 4—4 of Figure 3, looking downwardly.

Figure 5 is a perspective of the ejector comprised in the device.

Figure 6 is a fragmentary vertical section illustrative of the manner in which a package of cigarettes or other article of commodity is removed from the delivery chute.

Figure 7 is a fragmentary vertical section, on an enlarged scale, illustrating the manner in which the ejector is adapted to be moved past the catches.

Similar numerals of reference designate corresponding parts in all of the views of the drawings.

Manifestly it is within the purview of my invention to form the different elements of the device of material compatible with their purpose, and therefore no reference to materials will be made herein, the materials employed not being of my invention.

Among other elements my novel device comprises a casing body 1, and fixed to and rising from the said casing body 1 is an upright container 2, adapted to hold in superposed relation a plurality of packages or articles of commodity such as packages of cigarettes, designated by 3. At its upper end the container 2 is provided with a normally locked door 4, and is therefore adapted to be supplied with cigarettes or other articles of commodity at intervals, as occasion demands. In its forward wall 5 the container is provided with a vertical central sight glass 6, the purpose of which is to enable a person in authority to see when the container 2 requires replenishing.

As a whole my novel device is very narrow and compact, as shown in Figures 1 and 2, and therefore the device lends itself to the arrangement of a number of the devices in side by side relation in a narrow space, for the vending of a number of different articles of commodity. Toward such end, the upright container 2 is provided with front and rear lateral arms 7, notched at 8, and is also provided with front and rear members preferably in the form of pins 9, Figures 1-3.

Thus it will be apparent from the foregoing that because of the provision just described, a plurality of the devices may be coupled together in side by side relation so that there is no liability of any one of the devices being casually displaced, and the devices so arranged may be used for the vending of different kinds of cigarettes or for the vending of different articles of commodity, and when it is necessary one of the devices may be expeditiously and easily removed from the aggregation, and may thereafter be as readily united with the aggregation.

Disposed longitudinally in the casing body 1 is a delivery chute or conduit 10, which is preferably, though not necessarily, curvilinear as illustrated, and is closed at its upper and rear end as designated by 11. At its lower and forward ends the delivery chute 10 is provided with a door 12, hinged at 13 and equipped with a handle 14. It will also

be observed by comparison of Figures 3 and 6 that the door 12 is provided with an angularly disposed platform 15, the said platform resting when the door 12 is closed flush with the bottom wall of the chute 10, and being therefore adapted when the door 12 is swung to open position to carry before it a package of cigarettes so that following the opening of the door 12 the package of cigarettes will rest in the position shown in Figure 6 for ready removal from the door and from the device. On the return of the door 12 to its normal closed position, the platform 15 will be automatically positioned flush with the bottom wall of the chute 10 to receive a following box of cigarettes.

The equipment described of the door 12 constitutes an important feature of my invention, inasmuch as it renders it unnecessary for the purchaser to reach into the chute 10 for the package of cigarettes purchased. On the other hand when the door 12 is opened subsequently to an operation of the device, the package of cigarettes will be found on the door 12 and in front of the platform 15 in position for quick and convenient grasping of the package and removal thereof.

30 The ejector of my improvement is designated by 16, and is capable of being moved rectilinearly on a horizontal wall 17 in the casing body 1, the said wall 17 being spaced below different portions of the top of the casing body 1, and being also located in spaced relation below the lower end of the upright container 2, a hinged door 18 being located between the rear end of the wall 17 and the lower end of the back wall of the container 2 so as to permit of the rearward movement of the lowermost package of cigarettes from the wall 17 into the chute 10, and being also adapted subsequently to said movement of the lowermost package of cigarettes, to gravitate to the closed position shown in Figure 3. The said hinged and gravitational door 18 at the point indicated is desirable because it makes necessary a full rearward stroke of the ejector 16 in order 45 to transfer the lowermost package of cigarettes from the container 2 to the chute 10, and in that way assures dropping of the superposed packages 3 in the container 2 subsequently to the movement of the lowermost package from the wall 17 to the upper end of the chute 10.

In the preferred embodiment of my invention the rear portion of the ejector 16 is comparatively thick, is channeled at its upper side as designated by 19, and is undercut at its forward end as designated by 20. At the forward end of its forward comparatively thin portion the ejector 16 is provided with an appropriate handle 21, and in the preferred embodiment of my invention the

ejector has formed in said thin portion two forward circular apertures 22, and in rear of the said apertures 22 the ejector is provided in its said thin portion with a series of three circular apertures, the central aperture of said series being numbered 23 and the outer apertures thereof being numbered 24. The apertures 24 are in longitudinal alignment with the apertures 22, as appears in Figures 4 and 5. Retractile springs 25 located in the channels 19 are employed for the movement of the ejector 16 back to normal position subsequently to the rearward movement of the ejector 16 by a purchaser and the release of the ejector. Said springs 25 are connected at their forward ends to the top of the casing body 1 and their rear ends to the end portion of the ejector 16.

The said top wall of the casing body 1 is numbered 26, and it serves to house and protect the rear portion of the ejector 16 and the springs 25 complementary thereto.

In the wall 17 of the casing body 1 is provided a plurality of apertures 27, Figures 3, 4 and 7, for the reception and play of beveled heads 28 comprised in spring catches, the resilient shanks 29 of which are fixedly connected to the wall 17 as designated by 30. At a point in rear of the said apertures 27, which are arranged in a transverse series, Figure 4, is an opening 31 formed in the wall 17 in order to enable coins which have functioned to drop from the ejector 16 to the money receptacle 32 of the device, the said money receptacle being provided at its forward end with a normally closed and locked door 33, Figures 1 and 3.

A tray 34 is carried on the front wall of the casing body 1 and is connected by an opening 35 with a compartment 36 disposed above the forward portion of the money receptacle 32. The compartment 36 is in communication with openings 37 in the wall 17, and hence it will be understood that on the idle forward movement of the ejector 16 in the event of insufficient or improper coins having been placed in the apertures 22, 23 and 24 of the ejector, the said coins will drop from the ejector 16 through the opening 31, a single opening 37 being preferably employed, to the compartment 36 from which the said coins will pass to the tray 34 for the return of the coins to the prospective purchaser.

In the practical operation of my novel device, the proper coins are deposited in the apertures 22-24 of the ejector 16, and the said ejector is then moved rearwardly against the action of the springs 25. The rectilinear movement of the proper coins in the ejector will serve on the said rearward movement of the ejector to hold the catches 28 in depressed position, and hence the ejector will operate to displace a package from the container 2, whereupon said package will

gravitate to the platform 15 at the forward end of the chute 10 to be removed on the opening of the door in the manner made manifest by Figure 6. On the release of the 5 ejector 16 the springs 25 will operate to promptly return the ejector to its normal position, there being no liability of any portion of the ejector catching on the heads of the catches 28 because of the beveled rear 10 ends of the said catches as is best shown in Figure 7. It will also be apparent that on the displacement of the lowermost package in the container 2 and the transfer of said 15 package to the chute 10, the superposed series of packages in the container 2 will gravitate so that the lowermost package thereof will rest on the wall 17 in the path of the ejector 16 and in readiness for another 20 operation of the device.

It will be apparent from the foregoing 25 that my novel device while simple and inexpensive in construction is well adapted to withstand the usage to which vending devices are ordinarily subjected.

It will also be appreciated that the device 30 is susceptible of being expeditiously operated as is desirable when a number of persons are to be served in quick succession. I would have it distinctly understood that 35 it is within the purview of my invention to provide the ejector with one, three, five or any other desired number of apertures for the reception of coins, the catches 28 corresponding in number to the longitudinal 40 sets of ejector apertures employed. I would also have it understood that when a number of my devices are arranged in a battery or aggregation as before alluded to, the ejectors of the several devices may be provided with 45 different numbers of coin receiving apertures. For instance one ejector may be provided with five apertures, as shown, for the reception of five nickels necessary to the purchase of a package of cigarettes costing twenty-five cents, while the ejector in another one of the devices may have only the apertures 23 and 24, the apertures 22 being altogether omitted.

The construction herein illustrated and

described in detail constitutes the best practical embodiment of my invention of which I am cognizant and has been disclosed as stated in order to communicate an exact understanding of the same. I do not desire, however, to be understood as confining myself to the specific construction and relative arrangement of the parts as disclosed, my invention being defined by my appended claim within the scope of which various structural changes may be made without departure from my invention.

Having described my invention, what I claim and desire to secure by Letters-Patent, is:—

A vending device comprising a casing 65 body, a delivery chute therein, a support in the casing body for superposed articles of commodity and extending to the upper wall of the chute at the upper end of said wall, a container for said articles having its lower 70 end open and spaced above said support and also having its rear wall spaced above said upper end of the chute wall, a wall extending forwardly from the lower end of the forward wall of the container and spaced 75 above said support to form therewith a housing, an ejector movable rectilinearly between the support and said forwardly projecting wall and having a rear comparatively thick portion and longitudinal channels in 80 the upper side of said portion and also having a forward low comparatively thin portion and a handle at the forward end thereof, retractile springs for returning the ejector to normal position, said springs resting 85 in the longitudinal channels in the ejector and connected at their forward ends to said forwardly projecting wall and at their rear ends to the rear end of the ejector, and a swingable member disposed below the rear 90 wall of the container and hingedly connected with the casing body and adapted to gravitate to closed position at the rear end of the support.

In testimony whereof I affix my signature.

FLOYD JAMES McFARLAND.
